UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

WATER-MOTOR.

1,327,953.

Specification of Letters Patent. Patented Jan. 13, 1920.

Application filed August 6, 1918. Serial No. 248,506.

To all whom it may concern:

Be it known that I, JOHN R. HAMILTON, a citizen of the United States, residing at Yonkers, county of Westchester, State of New York, have made a certain new and useful Invention Relating to Water-Motors, of which the following is a specification, taken in connection with the accompanying drawing, which forms part of the same.

10 The invention in this case, which is a partial continuation of my co-pending application, Serial No. 98,756, filed May 20, 1916, relates especially to water motors particularly adapted for use with the alarm gongs 15 of automatic sprinkler apparatus. During the operation of such apparatus in the event of fire, a jet or stream of water is supplied to the motor to operate the same and thus sound the connected alarm gong or other 20 signal to call attention to the fire or emergency condition of the apparatus. The motor may advantageously comprise a sectional motor casing, the motor wheel and connected motor shaft being supported in bearings 25 permanently mounted in the main casing section which also carries the nozzle, so that the coöperating removable casing section may be removed and adjusted without disturbing the motor bearings or the alinement 30 of the wheel with the nozzle. The nozzle is preferably upwardly directed toward the motor wheel which minimizes the undesirable entrance of dirt and the nozzle is protected by one or more screens or perforated 35 shields deflecting large particles of rust or dirt to the bottom of the nozzle chamber where they will not interfere with the passage of the motor fluid to the nozzle and may be conveniently removed.

40 In the illustrative embodiment of the invention shown in the drawings, Figure 1 is a transverse section through the motor and shaft, and

Fig. 2 is a longitudinal section thereof 45 taken substantially along the line 2—2 of Fig. 1.

In the illustrative embodiment shown in the drawings the motor may comprise a sectional casing in which the casing cover 1 is joined to the motor casing 2 at a point substantially above the bearings of the motor so that they are not in any way disturbed when the casing cover is removed and consequent derangement or cramping of the 50 bearings is thus prevented. These two cas-

ing members are of course rigidly secured together as by the bolts indicated, and a tight joint may be made between them as by the packing 3. The motor shaft 13 may be mounted in suitable bearings within the lower section or motor casing 2, these bearings being, if desired, suitable self-aligning bearings 15 which may be graphite impregnated. In some cases these bearings may with advantage be loosely or swivelingly 65 mounted directly in the motor casing as by being mounted in the cylindrical or other suitable sockets 16 thereon and loosely retained in position as by the retainer screws 17. The wheel 11 may be rigidly mounted 70 on this motor shaft as by a suitable key or pin 52 engaging the shaft and the wheel hub, and buckets 12 similar to the Pelton type may be arranged on the wheel so as to cooperate most advantageously with the motor 75 nozzle.

The coöperating motor nozzle, such as 9, is preferably arranged in a somewhat upwardly inclined position adjacent the bottom of the casing where it is not only supported by the permanently mounted section of the casing, but is also more likely to maintain its continued clear and effective condition. The nozzle as indicated may be readily screwed into the threaded nozzle hole 49 in 80 the casing by turning the nut 57 on the extension arms 56 formed on this nozzle, which may have slipped over the arms so as to be mounted in connection therewith, the cylindrical or other screen 8, removing any dirt 85 or impurities from the motive fluid before it enters the nozzle to act on the wheel and finally be discharged from the casing through the waste pipe 14. If desired, a suitable perforated shield or guide screen, 90 such as 6, may be secured to the removable cap 55 or otherwise mounted substantially annularly around this screen within the nozzle casing 4 thus forming the nozzle drain 95 chamber 5. The supply pipe 10 may communicate with the chamber at any convenient point preferably adjacent the supporting wall as indicated so that the water or other motive fluid passes up around and through the guide screen and then through 100 the nozzle screen 8 before entering the nozzle, particles of dirt or the like thus being more certainly deflected into the chamber below from which they may be removed when the 105 plug 7 is taken out.

The motor casing may be mounted in any suitable way as by forming a motor bracket 22 integral with the lower or main casing section 2 and this motor bracket may be 5 bolted or otherwise secured to the wall 47 in any desired way. For some purposes it is desirable to have an alining or connector tube 23 extend through this wall and the motor bracket may be connected thereto by 10 having this tube pass through a suitable aperture in the alining collar 53 in this bracket while a holding nut 21 screwed on the end of the tube holds the bracket thereto. The motor shaft 13 may have a suitable 15 coupling 19 pinned or otherwise rigidly secured thereto so as to coöperate with the driving or alarm shaft 24 which may extend into the square or other polygonal hole 20 in the coupling and through this alining 20 connecting tube 23 to drive the connected gong or other alarm device not shown in the drawing which may be mounted on the outside of the wall, for instance. It is also advantageous to have the dust case or shield 25 50 bridge the space between this coupling and the connector tube to prevent dirt or dust collecting on the adjacent moving parts, and this dust case may be bolted to the casing cover as by the one or more bolts 51 so 30 as to be removable therewith when the motor wheel is inspected or cleaned.

This invention has been described in connection with a number of illustrative embodiments, parts, forms, sizes, proportions, 35 materials and arrangements, to the details of which disclosure the invention is not of course to be limited, since what is claimed as new and what is desired to be secured by Letters Patent is set forth in the appended 40 claims:

1. In water motors adapted for alarm gongs, a sectional motor casing, a motor wheel and connected motor shaft supported in bearings in the lower section of said motor casing, said casing having a removable top section above said bearings, a nozzle chamber formed adjacent the bottom of said casing, a nozzle projecting through the wall of said chamber to coöperate with said wheel, 45 a tubular screen in said chamber coöperating with the inlet end of said nozzle, a supply pipe connected to said chamber at the side of said chamber and screen, a deflecting shield located between said screen and said 50 supply pipe to deflect dirt, etc., to the bottom of said nozzle chamber, and a removable plug in the bottom of said nozzle chamber.

2. In water motors, a motor casing comprising a nozzle chamber and nozzle, a removable casing cover coöperating with said motor casing, said motor casing being formed with cylindrical bearing sockets extending transversely through the one piece casing adjacent said casing cover, self-alining 65 bearings in said bearing sockets and re-

tainer means loosely engaging said bearings and holding them in said sockets, and a motor wheel and connected motor shaft coöperating with said bearings.

3. In water motors, a sectional motor casing to substantially inclose a motor wheel, a motor wheel and connected motor shaft supported in self-alining bearings in the main section of said motor casing, said casing having a removable section beyond said 70 bearings, a nozzle chamber formed adjacent the bottom of said casing, an upwardly discharging nozzle projecting through the wall of said chamber to coöperate with said wheel, arms and a connected operating nut 75 connected to said nozzle and extending into said chamber, a screen in said chamber removably supported by said arms to coöperate with the inlet end of said nozzle, a cap removably closing the end of said chamber opposite said nozzle and a supply pipe connection communicating with said chamber.

4. In water motors, a motor casing to substantially inclose a motor wheel, a motor wheel and connected motor shaft supported in bearings in said motor casing, a nozzle chamber formed adjacent the bottom of said casing, a nozzle projecting through the wall of said chamber to coöperate with said 90 wheel, arms and a connected operating device connected to said nozzle and extending into said chamber, a screen in said chamber removably supported by said arms to coöperate with the inlet end of said nozzle, a cap removably closing the end of said chamber opposite said nozzle and a supply pipe connection communicating with said chamber.

5. In water motors, a motor casing to substantially inclose a motor wheel, a motor wheel and connected motor shaft supported in bearings in said motor casing, a nozzle chamber formed adjacent the bottom of said casing, an upwardly discharging nozzle projecting through the wall of said chamber to coöperate with said wheel, arms and a connected operating device connected to said nozzle and extending into said chamber, a screen in said chamber removably supported by said arms to coöperate with the inlet end of said nozzle, a cap removably closing the end of said chamber opposite said nozzle, a supply pipe connection communicating with said chamber, and a deflecting shield in said 100 chamber between said supply pipe connection and said screen to deflect therefrom dirt, etc.

6. In water motors, a sectional motor casing, a motor wheel and connected motor shaft supported in bearings in the main section of said motor casing and adjacent the edge thereof, said casing having a removable section beyond said bearings to permit access to and removal of said wheel, a noz- 125 130

zle projecting through the wall of the main section of said casing to coöperate with said wheel, and a screened supply pipe connection communicating with the inlet end of 5 said nozzle.

7. In water motors, a sectional motor casing, a motor wheel and connected motor shaft supported in bearings in the main section of said motor casing, said casing having a removable section beyond said bearings 10 to permit access to and removal of said wheel, a nozzle chamber formed adjacent the bottom of said casing, a nozzle projecting through the wall of said chamber, a 15 screen coöperating with the inlet end of said

nozzle and a supply pipe connected to said chamber adjacent said screen.

8. In water motors, a sectional motor casing, a motor wheel and connected motor shaft supported in self-aligning bearings permanently and loosely retained in bearing sockets in the main section of said motor casing, said casing having a removable section beyond said bearings, a nozzle projecting through the wall of the main section of 20 said casing to coöperate with said wheel, and a supply pipe connection communicating with the inlet end of said nozzle. 25

JOHN R. HAMILTON.
